UNITED STATES PATENT OFFICE.

JOSEPH B. KASSER AND MORRIS KASSER, OF SAN FRANCISCO, CALIFORNIA.

LIFE-PRESERVER.

1,130,297.

Specification of Letters Patent. Patented Mar. 2, 1915.

Application filed June 8, 1914. Serial No. 843,893.

To all whom it may concern:

Be it known that we, JOSEPH B. KASSER and MORRIS KASSER, citizens of the United States, and residents of the city and county of San Francisco and State of California, have invented a new and useful Improvement in Life-Preservers, of which the following is a specification.

Our invention relates to life preservers wherein a garment or belt is provided with a series of inverted pockets adapted to be automatically inflated by the action of the wearer when dropping into the water, and to contain a series of water tight bags that may be inflated either before or after the wearer enters the water; and the objects of our invention are first, to provide an improved life preserver having inverted pockets adapted to be partially inflated when the wearer drops into the water; second, to provide a device of the character described wherein the air within the pockets will be confined therein by the pressure of the water; third, to provide improved means for further inflating the pockets; and fourth, to provide a life preserver that will lie perfectly flat and thus require little room for storage on board vessels and the like. We accomplish these several objects by means of the device disclosed in the drawings forming a part of the present specification wherein like characters of reference are used to designate similar parts throughout the said specification and drawings and in which—

Figure 1 is a broken elevation of a life preserver extended or opened out, disclosing a plurality of inverted pockets therein, a separate inflatable bag in each pocket, and the connections whereby each bag may be inflated. Fig. 2 is a perspective view of the life preserver as it would appear secured to the person. Fig. 3 is a detailed view of one of the valves.

Referring to the drawings, the numeral 1 is used to designate a belt folded upon itself, so that the lower outer edge 2 is slightly above the lower inner edge 3 thereof. The belt 1 is stitched at intervals, as at 4, so as to provide a series of inverted pockets 5. Shoulder straps 6 are secured to the upper edge of the belt 1, while suitable buckles 7 are provided on one end of the belt 1 and adapted to engage the straps 8 on the other end thereof. Within each pocket 5 is a deflatable bag 12 having a

valve 14 secured to the lower end thereof and communicating with a circumferentially disposed tube 15, which runs along the lower edge of the belt and has the end thereof projecting above the belt as at 16. When stored aboard-ship, the bags 12 are deflated by removing the valves 14 therefrom and pressing the said bags 12 in order to exclude all the air therefrom. The valves 14 are then re-inserted or connected to the bags 12 and the belts 1 are piled upon each other, and being deflated and flat, will occupy very little space when so stored.

In using the belt 1, it is secured to the person and assumes the shape disclosed in perspective in Fig. 2 of the drawings. When the preserver is strapped to the person and the wearer drops into the water, a quantity of air will find its way under the edge 2 and into the pockets 5. As the person drops into the water, inasmuch as the pressure of the water on the bags increases in proportion to the depth, it will be readily seen that the greater pressure will occur at the lower portion of the inverted pockets 5 and consequently, the air therein will be imprisoned, such imprisoned air being sufficient to keep the body afloat.

In order to increase the buoyancy of the belt 1, the wearer of the said belt may inflate the bags 12 by blowing into the end of the tube 15, which extends above the belt, as at 16, and directly in front of the wearer. As the bags 12 are inflated, the pressure of the expanding bags will force the air out of the pockets 5, but at the same time will blow sufficient air into the bags 12 to take the place of the air so expelled from the inverted pockets 5. A valve 14 is provided for each bag 12, for the purpose of admitting the air thereto, but is adapted to prevent the escape of the air from the said bags 12. This arrangement is provided so that all of the bags will have an equal buoyancy. For instance, if the person in the water should lean to the right side, the increased pressure of the water would cause the air to be expelled from the bags 12 on that side, if it were not for the valves 14 which will prevent such escape of air, and force the air into the bags 12 on the left side, making that side more buoyant and consequently the person would be suspended in the water in an uncomfortable or even dangerous angle; but inasmuch as the air cannot escape from one of the bags into one of the adjoin-

ing bags, it is evident that the belt will have its buoyancy equally distributed and the person will be suspended in the water in an upward position. A further advantage of 5 the belt, herein described, is that should a portion of the air escape from the bags, rendering them less buoyant, the full buoyancy may be restored by blowing into the tube 15. Even in case of a serious leak in some of the 10 bags, the wearer could maintain himself and float for a considerable length of time by blowing into the bags. We have provided the clasp buttons 10 at the bottom of the inverted pockets 5 for the purpose of retaining the bags 12 within the said pockets.

In case the life preserver belt is to be washed, by unfastening the clasp buttons 10 at the lower edges of the pockets 5, the tube 15 and bags 12 may be easily removed 20 therefrom, so that the said bags 12 and tubes 15 will not be injured by the washing or from being passed through a wringer. After washing the device the bags 12 and tubes 15 may be easily inserted into their 25 proper positions and the bags 12 retained in their pockets 5 by fastening the clasp buttons 10.

It is obvious from the foregoing that we have provided an improved life preserver, 30 which will be automatically inflated when the wearer drops into the water; also means for further inflating the preserver, either before or after the wearer is in the water.

We are aware that the present state of the 35 art discloses life preservers having pockets arranged to contain inflated bags therein, we therefore do not wish to claim as our invention such a combination broadly, but

What we do claim and desire to secure by 40 Letters Patent is—

1. A life preserver comprising a belt having a plurality of pockets therein, said pockets being open at their lower ends and having the inner sides thereof extending be-

low the outer sides; and means for inflating 45 the pockets.

2. A life preserver comprising a belt having a plurality of pockets therein open at the lower ends thereof, the inner sides of the said pockets extending below the bottom of 50 the outer sides thereof; inflatable bags within the pockets; and means for inflating the inflatable bags.

3. A life preserver comprising a belt having a plurality of pockets therein open at 55 the lower ends thereof, the inner sides of the said pockets extending below the bottom of the outer sides thereof; inflatable bags within the pockets; means for inflating the inflatable bags; and means for retaining the 60 air within the bags when inflated.

4. A life preserver comprising a belt having a plurality of pockets therein open at the lower ends thereof, the inner sides of the said pockets extending below the bottom of 65 the outer sides thereof; inflatable bags within the pockets; means for inflating the inflatable bags; and suitable valves adapted to retain the air within the bags.

5. A life preserver comprising a belt having a plurality of pockets therein open at their lower ends, inner sides of the said 70 pockets extending below the bottom of the said pockets; inflatable bags within the pockets; a suitable valve secured to each bag 75 and adapted to retain the air therein; and a tube extending above the top of the front portion of the belt and connected with all of the valves secured to the bags and adapted to inflate the said bags through the valves. 80

In witness whereof, we hereunto set our signatures in the presence of two subscribing witnesses.

JOSEPH B. KASSER.
MORRIS KASSER.
